UNITED STATES PATENT OFFICE.

ANNA M. ANCHORSTAR, OF NEW YORK, N. Y.

ATTACHMENT FOR CORSETS.

1,308,025.

Specification of Letters Patent.

Patented July 1, 1919.

Application filed October 22, 1917. Serial No. 197,768.

To all whom it may concern:

Be it known that I, ANNA M. ANCHORSTAR, a citizen of the United States, and resident of the city of New York, in the county of New York and State of New York, have invented certain new and useful Improvements in Attachments for Corsets, of which the following is a specification.

The invention relates to improvements in wearing apparel. More particularly this invention relates to women's corsets. The object of the invention is to provide an attachment for corsets adapted to be manufactured as a separate commercial article or embodied in the construction of the corset for the purpose of preventing it from "creeping up" and becoming displaced.

Because of an enlightened public opinion with reference to the proper clothing and personal hygiene it is no longer desirable that corsets be worn laced very tight. This is also due to a change in fashion to dress along the natural lines of the body and corsets are no longer required to be laced so tight as to produce the "wasp effect" which formerly was thought to be very desirable, but which medical science condemns.

On the other hand, when a corset is not laced very tight it is apt to work up or creep up on the body of the wearer, thereby producing discomfort and spoiling the effect of careful dressing. It also tends to tear the stocking because the garters are attached to the corset.

It is therefore the object of this invention to provide a means for keeping the corset down in proper position.

To this end my invention is embodied in an article of manufacture as hereinafter disclosed and illustrated in the accompanying drawings in which—

Figure 1 is a side view of a corset with my attachment secured thereto in proper position;

Fig. 2 is a view showing the attachment and corset as they appear when worn upon the body;

Fig. 3 is a separate view of the attachment; and

Fig. 4 shows a modification.

The reference numeral 5 denotes the corset which may be of any usual construction. 6 indicates the front of the corset and 7 the back. 8 are the hose supporters.

My attachment comprises a piece of elastic material 9 adapted to be secured to the corset as by sewing 17 along the upper, preferably straight, edge 12, and of a width from the front edge 10 to the rear edge 11 sufficient to partially surround and encircle the leg of the wearer on the outside thereof from the lower edge of the corset and to below the knee. In order to conform to the curves of the body when sitting and to exert an even downward pull upon practically the entire lower portion of the corset 5, the attachment is made in one piece with the front edge 10 longer than the rear edge 11. The bottom edge 13 is cut so as to be clasped horizontally around the leg below the knee by means of the strap 14—15, which may be secured and adjusted by a buckle 16 of any suitable construction.

The attachment possesses certain advantages due to its elasticity, shape and size. Thus by being attached to the corset for a distance covering more than one-half on either side an even, strong, yet easy, downward pull is exerted upon the corset and the lower portion of the latter is kept snugly against the body without bulging, crimping or wrinkling, such as is the case when only separate straps are used for this purpose. Again, the difference in length of the front and rear edge causes the even downward pull on the corset to be maintained while the wearer sits down, in which case the line passing from below the knee and over the latter is longer than the opposite line on the underside of the leg. When the wearer is standing this difference in length is taken up in that the corset on the side is longer than in front or back.

The width of the attachment is such that it covers at least one-half of each side of the corset, it being understood that for each corset there will be used one attachment on either side as shown.

In securing the attachment to the corset care should be taken to place the front edge 10 so close to the front 6 that said edge will coincide with a line passing in front of the leg directly over the knee.

After the corset has been laced, the strap 14—15 is clasped around the knee inside the stockings after which the garters are attached as usual. If the garters are spaced so as to be directly beneath the attachment,

slits 18 may be provided in the latter as shown in Fig. 3, through which the garters may be passed.

In Fig. 4 the attachment is built in as a part of the corset.

I have found by wearing the attachment that it may be worn without discomfort, keeps the corset down perfectly and stretches sufficiently in bending.

10 The strap 14—15 may extend to both sides or be a separate piece sewed across the lower portion of the attachment. Other modifications may be made within the scope of the invention without departing from the principle thereof.

I claim.

1. As a new article of manufacture, an attachment for corsets comprising a body portion of elastic material, one for each side 20 of the corset, said body portion having four edges, a top edge long enough to extend from near the front edge of the corset to near the rear edge of the corset, the front

edge of the body portion being longer than the rear edge thereof and the bottom edge 25 being substantially shorter than the said top edge and means for securing the said bottom edge to the leg of the wearer below the knee.

2. As a new article of manufacture, an attachment for corsets comprising two solid body portions of elastic material adapted to be attached to the corset, one on each side, said body portions extending downwardly from the sides of the corsets to below the 35 knees of the wearer and shaped to partially encircle the legs on the outside thereof from front to back, said body portions being provided with slits for the passage of the hose supporters of said corset and means for securing the body portions below the knees of the wearer.

Signed at New York, in the county of New York and State of New York this 20th day of Oct. A. D. 1917.

ANNA M. ANCHORSTAR.
